[57] CLAIM

The ornamental design for a combined heating pad and adjustable belt, as shown and described.

DESCRIPTION

FIG. 1 is a front, top and side perspective view of the combined heating pad and adjustable belt showing my new design in the disassembled condition, the electric cords connecting the power pack on the adjustable belt to the joint bandage and to power being broken away for the sake of convenience of illustration;

FIG. 2 is a front elevational view thereof;

FIG. 3 is a rear elevational view thereof;

FIG. 4 is a side elevational view thereof;

FIG. 5 is a side elevational view thereof;

FIG. 6 is a top plan view thereof;

FIG. 7 is a bottom plan view thereof; and,

FIG. 8 is a perspective view thereof in an assembled state.
